PAPER HOLDER

West Henson and William Nelson, Jr.,
New York, N. Y.

Application August 26, 1936, Serial No. 98,012

1 Claim. (Cl. 242—107)

This invention relates to a carrier for a roll of paper upon which memoranda may be written.

It is an object of the invention to so form the paper holder that a roll of paper may be mounted in a tubular housing and the shaft of the roll of paper yieldably held against rotation in an unwinding direction. Therefore, the paper may be withdrawn and notes written thereon and the strip of paper rewound about the roller, or, if so desired, a portion of the strip of paper may be drawn off of the roll and detached therefrom either before or after being written upon.

The invention is illustrated in the accompanying drawing, wherein.

Figure 1 is a longitudinal sectional view through the combined pen, pencil and paper holder.

Figure 2 is a view showing the paper holder in longitudinal section.

Figure 3 is a sectional view taken transversely through the paper holder upon the line 3—3 of Figure 2.

Figure 4 is a sectional view through the paper holder taken along the line 4—4 of Figure 2.

This improved writing implement consists, briefly, of a tubular casing 1, which may be referred to as a sleeve or barrel, a fountain pen, indicated in general by the numeral 2, an automatic pencil, indicated in general by the numeral 3, and a paper roll carrier 4 which is housed within the body portion or barrel of the automatic pencil and a portion of the fountain pen barrel when the automatic pencil and the fountain pen are thrust into the casing 1. The barrel 5 of the fountain pen fits snugly within the sleeve or casing 1 with a thickened portion projecting from one end of the casing and defining a shoulder 6 for engaging the end of the tubular casing and limiting movement of the fountain pen barrel into the casing. Companion threaded portions are provided upon the fountain pen barrel and within the casing, as shown at 7, so that when the fountain pen barrel is thrust into the tubular casing and then turned to effect engagement of the companion threaded portion, the fountain pen will be securely but detachably held in engagement with the casing. The automatic pencil also has a barrel 8 which fits snugly within the casing 1, and the portion 9 of this barrel which projects from the casing at the opposite end thereof from the fountain pen is externally thickened to provide an annular shoulder 10 to limit inward movement of the barrel 8 into the tubular casing. Companion threads 11 corresponding to the threads 7 are

provided in order that the barrel of the pencil may be securely but releasably held in the tubular casing. It will thus be seen that the fountain pen and the automatic pencil may be thrust into the tubular casing from opposite ends thereof and securely but detachably held therein with inner ends of the barrels 5 and 8 contacting with each other intermediate the length of the tubular casing and the inner end portion of the barrel 5 serving as a closure for the chamber 12 formed longitudinally in the barrel of the pencil and of such diameter that the paper holder 4 may be housed in this chamber 12.

The paper holder is constructed, as illustrated in detail in Figures 2, 3 and 4. This paper holder, which is indicated in general by the numeral 4, has a cylindrical barrel 57 having one end open and internally threaded, as shown at 58, to receive an externally threaded closure plug 59. At its other end the barrel is formed with a head 60 having a central opening through which extends the neck 61 of a block 62 which is substantially cylindrical in shape and fits snugly in the barrel 57. A bore 63 is formed through the block 62 axially thereof with its inner end portion of increased diameter to form a seat 64 and through the bore extends a stem 65 having at one end a disc-shaped head 66 which fits into the seat 64 and is notched diametrically at 67 to receive the rib 68 at one end of the shaft or roller 69 upon which the note paper 70 is wound. The rib 68 and the notch 67 of the head 66 constitute companion clutch members serving to cause the stem and the roller to turn together. The other end of the roller is rotatably received in the socket 71 formed centrally of the plug 59. Therefore, the roller will be mounted between the plug and the stem and the paper may be drawn outwardly through the slot 72 formed in the casing. In order to yieldably resist rotation of the roller in a direction to unwind the paper, there has been provided a spring 73 of the helical type which is coiled about the stem within the bore 63 and has its inner end anchored to the head 66 and its outer end embedded in the neck 61 of the block. A tongue 74 which is cut from the barrel and extends circumferentially thereof engages a shoulder 75 of the block and prevents rotation of the block in one direction. Therefore, when the stem is turned to tension the spring, 50 the block will be held against rotation by tension of the spring and this spring will act to resist rotation of the roller in a direction to unwind the paper and cause the roller to be turned in a winding direction to rewind the paper after hav-

ing notes written thereon. The portion of the stem which projects from the neck of the block is squared, as shown at 76, to provide a shank which extends through a cap 78 and has its outer 5 end headed, as shown at 79, to retain the cap upon the shank 76. A squared opening 80 is formed in the cap to receive the squared shank 76 of the stem 65 and cause the stem to turn with the cap and in order to prevent retrograde 10 rotation of the cap by the helical spring 73 after the spring has been wound, there have been provided pawls 81 which pivot about pins 82 and are adapted to engage cooperating ratchet teeth 83 formed upon the neck 61 of the block 60. It 15 will thus be seen that since the block 62 is held against rotation in one direction by the tongue 74 and the cap is held against retrograde rotation by the pawls 81, the spring will be maintained under tension after it has been wound 20 and the strip of paper 70 may be drawn outwardly through the slot 72, memoranda written thereon and the paper then rewound upon the roller. If so desired, the portion of the paper drawn outwardly may be torn off either before or after 25 a memorandum has been written thereon.

When use of the paper is desired, the pencil may be unscrewed from the tubular sleeve, the paper holder withdrawn and either the pen or the pencil used for writing upon the portion of the 30 paper withdrawn from the paper holder. It will be obvious that, if so desired, the pen may be unscrewed from the tubular sleeve in order to remove the paper holder and it will also be obvious that after the paper holder has been re-

moved, the pen or the pencil which was removed in order to permit access to the paper holder may be returned to its position in the tube before writing upon the paper.

Having thus described the invention, what is 5 claimed as new is:

In a device of the character described, a paper holder comprising a cylindrical casing formed with a longitudinally extending slot, a bearing at one end of said casing, a block in the other end portion of said casing having a neck extending through the opening in the head of the casing, means to prevent rotation of the block in one direction, the block being formed with an axially extending bore, a stem rotatably received 15 in the bore of said block and having its inner end formed with a clutch member, a paper roller extending longitudinally in said casing with one end journaled in said bearing and its other end formed with a clutch member for engaging the 20 clutch member of said stem, a helical spring coiled about said stem within the bore of said block with one end anchored to the stem and its other end anchored to the block, a cap fitting about the outer end portion of said stem 25 and held against rotation thereon, the neck of said block being formed with ratchet teeth, and pawls carried by said cap for engaging the ratchet teeth of said neck to hold the cap and stem against retrograde rotation when the cap 30 and stem are turned in a direction to wind and tension said spring.
